UNITED STATES PATENT OFFICE.

JOHN HOLLAND LETZ, OF CROWN POINT, INDIANA.

GRINDING BURR.

Application filed January 14, 1920, Serial No. 351,301. Renewed January 28, 1924.

To all whom it may concern:

Be it known that I, JOHN HOLLAND LETZ, a citizen of the United States, and a resident of Crown Point, in the county of Lake 5 and State of Indiana, have invented certain new and useful Improvements in Grinding Burrs, of which the following is a full, clear, and exact specification.

My invention is concerned with grinding 10 burrs of the class shown in my Patent 1,244,516, dated October 30, 1917, in which the base has a flat annular portion upon which are formed outwardly extending ribs which have their tops ground off flat to 15 present shearing edges to co-operate with similarly formed shearing edges on the opposed burr, and is designed to produce a burr having a novel design and arrangement of the ribs so that it will grind satisfactorily such diverse articles as corn, oats, 20 beans, short hay, etc., and will have a longer life and operate more satisfactorily than one having the ribs designed as in my aforesaid patent.

25 To illustrate my invention, I annex hereto a sheet of drawings in which the same reference characters are used to designate identical parts in all the figures, of which—

Fig. 1 is a plan view of a portion of a 30 burr embodying my invention;

Fig. 2 is a central section on a reduced scale; and

Fig. 3 is a section on the line 3—3 of Fig. 1.

35 The base A is an annulus preferably a metal casting having the design in cross section as it appears in Fig. 3, with the inclined, depressed annular portion B surrounding the circular feeding opening, and the customary pair of annular ribs C and D on the back.

The grinding ribs are preferably arranged in similar sections, as shown, with each section occupying one-sixth of the face of the 45 burr. At the beginning of each section is a main rib E extending inward slightly beyond the inner edge of the annulus, as shown, and outward substantially at the angle shown to a radial line intersecting it, say one-half of the distance across the annulus, where it preferably has the short deflecting end e turned off at a greater angle to a radial line. The pair of these main ribs E bounding any section serve to guide 50 the material into said section.

In each section parallel to the main rib E are a plurality of ribs F, F', F², F³, F⁴, F⁵, F⁶, F⁷, F⁸, F⁹, F¹⁰, F¹¹, arranged in three parallel rows, and there is another row of similar parallel ribs G, G', G², and G³, parallel to the other three rows but with the ribs G, G', G², and G³ not strictly parallel to the ribs of the first three rows. Each of the ribs F, etc., and G, etc., consists of a straight body portion with preferably the deflecting ends f and g, although it will be understood that some of these ribs are mutilated and incomplete in their design because of their running into the perimeter of the burr. In addition to the aforesaid sets of ribs, I provide three somewhat similar ribs H, H' and H² parallel in their general outlines to the ribs of the rows of which they constitute the inner ends, but they, like the main ribs E, have their bases thickened to give additional substance and body to the ribs, as the wear from the grinding action is greatest on the inner portion of the burrs. In the row with the rib H², I may place the shortened ribs H³, H⁴, H⁵, H⁶, H⁷, H⁸, which constitute a sort of an aborted row back of the main rib E of the next section. All of the ribs so far described are cast so that their complete upper surface is ground off flat when the burr is dressed, and their entire advancing edges can have a shearing action if the material is against them when they meet the shearing edges of the opposed burr.

If the ribs so far described only were used, the material would pass across the face of the burrs too rapidly and it would not be properly ground. In my prior Patent No. 1,244,516 before referred to, to prevent this I placed lower intercepting ribs there marked M, etc., N, etc., O, etc., and P, etc., between the outer ends of the shearing ribs, and extending directly across the channel formed between the aforesaid main or shearing ribs. I have found that these low intercepting ribs wear out too rapidly, with the result that the burrs are soon grinding much more coarsely than is intended, and for that reason in my present burr, I have substituted for these intercepting or baffle ribs M, etc., N, etc., O, etc., and P, etc., of the old patent, the pairs of combined intercepting and grinding ribs L, which, as seen, have the angle in the outer ends to make their design conform to that

of the adjacent grinding ribs, but their inner ends, instead of having their top surfaces flush with the top surfaces of the shearing ribs as are the top surfaces of the outer ends, are tapered down, preferably to a point where they reach the surface of the plate. The action of these intercepting ribs L therefore is to slow up the passage of the material passing outward, if it is already ground fine enough to pass through the narrow channels remaining, but if it is too coarse to do so, it is forced up by the tapered inner ends to a level where it will be subjected to the action of the shearing edges and thus ground finer. These intercepting ribs present a much greater wearing surface to the grain than did the ribs M, etc., N, etc., O, etc., and P, etc., of my aforesaid patent, so that they produce a longer lived burr as well as one that grinds more effectively.

As the tendency of the rotation of the burr is to throw the material being ground generally toward the left, in order to spread it out over the entire surface between the adjacent shearing ribs, such as F³ and F⁴, for example, I place between each such pair of ribs and near the inner ends of the intercepting ribs L, the deflecting ribs M, which ribs are set at an angle to the line of the grinding ribs so that the material contacting therewith tends to be deflected to the right, thus counterbalancing the tendency of the material to go to the left, and thus distributing it better. As some of the material, especially if it is ground fine enough, should be permitted to follow the natural trend to the left, I bevel off, down to the lower surface of the plate, the inner ends of the ribs M, the outer ends of which have their top surfaces flush with those of the grinding ribs.

Extending generally inward from each of the deflecting ribs M will be noted the spaces N which have no teeth on them. These are provided to give room for elongated pieces of material, such as oat grains, to turn freely to get their longitudinal axes in alignment with the paths between the channels, and thus facilitate an even flow of the material between the burrs.

From the foregoing description of the construction and function of the various ribs, it is thought that the operation of the burr will be readily understood without any further description. At the outer edge, any spaces which would otherwise be vacant are filled by the short ribs, such as O, to prevent the premature escape of the material from the burrs.

While I have shown and described my invention as embodied in the form which I at present consider best adapted to carry out its purposes, it will be understood that it is capable of modification, and that I do

not desire to be limited in the interpretation of the following claims except as may be necessitated by the state of the prior art.

What I claim as new and desire to secure by Letters Patent of the United States is—

1. A grinding plate having on its surface plural series of long shearing ribs with their ground off tops in the same horizontal plane and arranged to form generally parallel passages set at a considerable angle to radial lines, together with plural series of short baffle ribs between the outer ends of the shearing ribs but not connected thereto and extending in a generally parallel direction to said outer ends, said shearing and baffle ribs being closely spaced so as to form narrow parallel channels for the ground material below the shearing ribs.

2. A grinding plate having on its surface plural series of long shearing ribs with their ground off tops in the same horizontal plane and arranged to form generally parallel passages set at a considerable angle to radial lines, together with plural series of short baffle ribs between the outer ends of the shearing ribs but not connected thereto and extending in a generally parallel direction to said outer ends, said baffle ribs having their inner ends tapered down from the shearing level to the body of the plate and pointing toward the material coming from the center of the plate.

3. A grinding plate having on its surface plural series of long shearing ribs with their ground off tops in the same horizontal plane and arranged to form generally parallel passages set at a considerable angle to radial lines, together with shorter deflecting ribs set between the shearing ribs toward the inner ends thereof but not connected thereto and extending at such an angle thereto that their inner surfaces tend to throw the material being ground toward the direction the plate is rotating.

4. A grinding plate having on its surface plural series of long shearing ribs with their ground off tops in the same horizontal plane and arranged to form generally parallel passages set at a considerable angle to radial lines, together with shorter deflecting ribs set between the shearing ribs but not connected thereto and extending at such an angle thereto that their inner surfaces tend to throw the material being ground toward the direction the plate is rotating, said deflecting ribs having their inner ends tapered down from the shearing level to the body of the plate and pointing substantially toward the center of the plate.

5. A grinding plate having on its surface plural series of long shearing ribs with their ground off tops in the same horizontal plane and arranged to form generally parallel passages set at a considerable angle to radial lines, together with plural series of

short baffle ribs between the outer ends of the shearing ribs and extending in a generally parallel direction to said outer ends, and shorter deflecting ribs set between the 5 shearing ribs adjacent the inner ends of the baffle ribs and extending at such an angle to the shearing ribs that their inner surfaces tend to throw the material being ground toward the direction the plate is rotating,

said baffle and deflecting ribs having their inner ends tapered down from the shearing level to the body of the plate.

In witness whereof, I have hereunto set my hand and affixed my seal, this 18th day of December, A. D. 1919.

JOHN HOLLAND LETZ. [L. S.]

Witness:

JOHN HOWARD McELROY.
